Primary Examiner — Lauren D McVey

CLAIM

The ornamental design for a cushion for mask for CPAP therapy, as shown.

DESCRIPTION

FIG. 1 is a perspective view of a cushion for mask for CPAP therapy showing my design with environment;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a perspective view of the cushion for mask for CPAP therapy showing my design without environment;
FIG. 9 is a front elevation view thereof;
FIG. 10 is a rear elevation view thereof;
FIG. 11 is a right side elevation view thereof;
FIG. 12 is a left side elevation view thereof;
FIG. 13 is a top plan view thereof; and,
FIG. 14 is a bottom plan view thereof.

The broken lines in the figures illustrate environment and form no part of the claimed design.

1 Claim, 11 Drawing Sheets

Related U.S. Application Data

having an international filing date of Oct. 9, 2015, now Pat. No. Des. 799,699.
